UNITED STATES PATENT OFFICE.

BERNARD F. SHAUGHNESSY, OF BROOKLYN, NEW YORK.

INCINERATOR.

Application filed October 7, 1925. Serial No. 60,960.

The invention relates to incinerators for burning garbage and other refuse, and aims to provide a novel and improved furnace of that kind which will be practical and efficient in operation and which will also consume the smoke and gas created by the combustion of the refuse.

Another object is the provision of an incinerator having a firebox and grate structure of novel and improved construction to increase the capacity of the firebox and facilitate the combustion of the material therein.

A further object is the provision of a novel door construction for the firebox in order that access may be had to the material in the firebox in a convenient and efficient manner for purpose of poking or stirring the material on the grate.

20 The invention has among its other objects to provide novel means for delivering the material into the furnace, novel means for reflecting and concentrating the heat in the combustion chamber, novel water circulating means, and novel features of construction and arrangement of the component elements of the incinerator.

25 The present incinerator is an improvement over the refuse incinerator disclosed in my Patent No. 1,479,875, granted January 8, 1924.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

30 The invention is illustrated in the accompanying drawings, wherein—

Figure 1 illustrates the improved incinerator, partly in side elevation and partly in vertical section.

35 Fig. 2 is an enlarged cross section on the line 2—2 of Fig. 1.

The furnace proper has the side walls 11 at the opposite sides of the combustion chamber, and composed of refractory bricks or other suitable material. The bricks composing the walls 11 are supported on longitudinal water chambers 12 extending the length of the combustion chamber, and said water chambers 12 are suspended by hangers 13 from longitudinal beams 14. Said beams 14 are supported by the end walls of the furnace struc-

ture or frame, and may be supported in any suitable manner, it being noted that the walls 11 being supported on the water chambers or members 12, and said members or chambers 12 being suspended from the beams 14, will support the walls 11 from said beams 14.

Longitudinal members 15 are disposed on the beams 14 and longitudinal drums 16 are seated on said members 15. The drums hold 65 water to be heated by the furnace. The drums 16 at the opposite sides are connected by cross pipes 17 to establish communication between said drums, and said pipes 17 also support the top 18 of the furnace, which 70 may be of bricks.

The top 18 of the furnace has an opening 19 through which the refuse is delivered into the furnace, and a chute 20 rises from said opening 19 and has a closed top. The opening 75 19 and chute 20 are elongated longitudinally of the furnace, and the chute 20 rises within a hopper 21 into which the refuse is dumped. The chute 20 has openings 22 in its opposite sides controlled by depending valves or shutters 23 which are hinged within the chute at their upper edges, to swing inwardly, and operating levers 24 are operably connected with said valves to swing them open and closed. With the refuse in the hopper 21 80 the valves 23 may be opened the desired amount to let the material drop down through the opening 19 into the furnace, and it is possible to control the delivery of the material into the furnace so as to avoid the 85 material packing within the furnace. This feeding arrangement for the furnace also avoids any possibility for workmen or attendants dropping into the furnace accidentally.

90 A water cooled basket grate is disposed within the combustion chamber of the furnace and includes longitudinally spaced sections, each of which has the vertical pipes 25 adjacent to the opposite side walls 11, 100 with their upper terminals 26 extending outwardly at right angles and journaled through the members 15. The lower terminals of the pipes 25 of each grate section are curved to converge toward one another and 105 are secured to a coupling 27. Couplings 28 are secured to the terminal portions 26 of the pipes 25 at the exterior of the furnace, and vertical pipes 29 have their upper ends connected to the couplings 28. Elbows 30 110 connect the lower ends of the pipes 29 with transverse pipes 31 that are also connected

to the coupling 27 of the grate section. The elbows 30 have handles 32 for conveniently swinging the grate sections, it being noted that said grate sections are suspended for 5 longitudinal swinging movement about the transverse axes of the portions 26 of the pipes 25. This enables the sections of the basket grate to be oscillated for loosening the material therein so that it will drop 10 down into the firebox underneath. Pipes 33 connected to the drums 16 have swivel connections with the couplings 28, so that said couplings may turn with the basket grate sections, and the pipes 33 also convey 15 the water to and from the drums. Water heated in the pipes 25 rises therein, while the cooler water will pass through the pipes 29 and 31 into the lower ends of the pipes 25, thereby establishing the circulation of 20 the water. The hot water will rise into the drums 16 from which it may be withdrawn.

The water chambers 12, which may have suitable inlets or outlets for the water, have face plates 34 extending downwardly at the 25 outer sides of the furnace, and provided with slots 35 through which the pipes 31 extend, thereby permitting the basket grate sections to be oscillated. The elbows 30 have closures 36 that cover the slots 35.

30 A base or bottom 37 of concrete or other suitable material is provided having the side walls 38 below the walls 11, and longitudinal air conduits 39 are mounted on the walls 38 at the inner sides thereof, and have inclined 35 side wall grates 40 at the tops thereof defining the lower portions of the sides of the firebox. The conduits 39 have lower openings 41 at their inner sides controlled by doors or valves 42 which may be opened by 40 any suitable means (not shown) to admit air into said conduits, or to discharge ashes and other accumulations therefrom. The conduits 39 have doors 42^a at the rear ends thereof, whereby the rear ends of the conduits may be opened to receive air so as to 45 discharge upwardly through the grates 40.

The ash pit 43 is located between the walls 38 below the bottom grate composed of the sections 44 which are mounted on transverse 50 rock shafts 45 that extend through the conduits 39 and walls 38, and suitable gearing 46 is provided for turning said shafts so that the grate sections 44 may be tilted to dump the material therefrom into the ash pit.

Rails 47 are mounted on the walls 38 and are spaced below the chambers or members 12 to provide openings in the sides of the furnace extending the length of the furnace. 60 A series of sliding doors 48 is mounted in each opening, and rollers 49 are preferably mounted in the rails 47 on which the doors move freely longitudinally. Flanged strips 50 are carried by the door 48 and engage 65 the lower edges of the plates 34 so as to

guide the doors for longitudinal movement, and each door has a handle 51 at the exterior so that the doors may be slid conveniently. It will be noted that the doors may be slid apart at any longitudinal point of the firebox, so that access may be had to the material on the bottom grate at any longitudinal point, for the insertion of a poker or other implement to stir the material. All of the doors 48 being slideable longitudinally will enable a poker or implement to be inserted at any longitudinal point of either side opening, and just sufficient opening can be provided between the separated doors as to admit the poker or implement without an excessively large opening into the firebox being necessary.

The doors 48 have refractory linings 52 to reflect the heat back into the firebox, and said linings have concaved recesses, as shown, for concentrating the reflected heat rays on the material so as to enhance combustion. Similarly, the inner surfaces of the bricks of the walls 11 may be concaved, as seen in Fig. 2, for reflecting and concentrating the heat rays on the material in the basket grate.

In rear of the ash pit 43 is a tunnel 53 into which air is discharged through a nozzle 54 from a suitable air blower (not shown). The air is discharged forwardly so as to pass into the ash pit 43 and up through the grate sections 44. Also, when the doors or valves 42^a are opened the air will be delivered into the conduits 39 to pass upwardly through the grates 40.

A track extends through the ash pit 43 and tunnel 53 and comprises the rails 55 mounted on the base or bottom 37, and a truck or car 56 is movable on the track, being run into the ash pit 43 below the bottom grate of the firebox so as to catch the ashes. A door 57 is provided at the rear end of the tunnel 53 to close the tunnel at this point, so as to prevent the flow of air through the rear end of the tunnel, and said door is slideable or movable out of the way for the passage of the truck 56 when moving the truck into or out of the incinerator.

In rear of the rear wall 58 of the furnace and above the tunnel 53 is a chamber or housing 59, and the rear wall 58 has a discharge opening 60 leading from the rear portion of the basket grate to a space 61 in the upper portion of the housing 59. Vertical transverse partitions 62, 63 and 64 are provided in the housing 59, and there is a vertical flue 65 between the partition 62 and wall 58, with a discharge opening 66 in the wall 58 leading from the rear end of the firebox into the flue 65. The products of combustion pass from the firebox through the opening 66 into the flue 65, and smoke and products of combustion from the basket grate pass through the opening 60 into the

space 61. Vertical flues 67 and 68 are provided between the partitions 62, 63 and 64, and open at their lower ends into the tunnel 53, and a valve 69 is provided to control the 5 opening between the upper end of the flue 67 and the space 61. A two-way valve 71 is hingedly mounted at the upper end of the partition 64 to control the flow down through the flue 68 and down through the flue or 10 space 70 in rear of the partition 64.

Separators for separating the ashes, soot and heavier particles from the gases are mounted in the partitions 62, 63 and 64, and include tubular members 72 in the partition 15 62 and tubes 73 extending through the partitions 63 and 64. The tubular members 72 are of larger diameter than the tubes 73 and the forward ends of the tubes 73 are located close to the members 72. The tubular members 72 are formed with grooves or 20 flanges to give the gases a whirling motion when passing through said members 72, whereby centrifugal action will throw the heavier particles away from the centers of 25 the streams of gases passing through the members 72 and tubes 73. Thus, the ashes, soot and other heavier particles are discharged into the flue 67 around the tubes 73, and will pass downwardly through the flue 30 67 into the tunnel 53 so as to be returned to the flames which will consume such particles. The lighter gases remaining at the centers of the streams will flow through the tubes 73 to the space 70 in rear of the partition 35 64.

In rear of the housing 59 is a second housing or chamber 74 extending from the housing 59 to the smoke stack 75 above the tunnel 53. The partition or wall between the 40 housings 59 and 74 has an opening 76, and the partition or wall between the housing 74 and stack 75 has an opening 77. A valve or damper 78 controls the opening 77. Within the housing 74 between the openings 76 and 77 are means for separating the smoke and green gases from the flames and products of combustion passing along the center of the flue-way leading from the opening 76 to the opening 77. Thus, a flange 79 extends rearwardly from the side and upper edges of the opening 76, and a flange 81 extends forwardly from the side and upper edges of the opening 77. Between the flanges 79 and 81 are arches 80. The flanges 55 79 and 81 and arches 80 are spaced apart and are of gradually decreasing size rearwardly from the opening 76 to the opening 77, thereby having a tendency to compress the gases as they flow rearwardly to the 60 stack. The flames and products of combustion pass through the central portion of the flue-way which leads through the members 79, 80 and 81 of the separating means, while the smoke and green gases move along 65 the sides and top of the flue-way and will be deflected and crowded through the slots between the members 79, 80 and 81, thereby separating the smoke and green gases from the more complete products of combustion that pass into the stack 75 through the opening 77.

The housing 74 has a space 82 therein above the members or separators 79, 80 and 81, with an opening 83 leading into the smoke stack 75 and controlled by a damper or valve 84. The space 82 has another discharge opening 85 controlled by a damper or valve 86, and a suction fan 87 communicates with the opening 85 and has its discharge portion 88 delivering into the smoke stack. 80 Disposed within the space 82 are grates or screens 89 on which is disposed filtering material 90, which may be coke, cinders, soil, or other suitable material to arrest particles of soot, ashes and other solid material that 85 enters the space 82.

In operation, the refuse is dumped in the hopper 21 and is delivered gradually into the furnace by controlling the valves or doors 23. The material delivered through 90 the opening 19 drops into the basket grate, and by delivering the material in small quantities into the furnace it will not pack in the basket grate. The material in the basket grate becomes heated and dried so that it 95 will burn, and the sections of the basket grate are shaken from time to time so that the dried material at the bottom of the basket grate will drop onto the bottom grate of the firebox. At first, the material accumulates 100 on the sections 44 of the bottom grate, and the doors or valves 42^a are closed so that no air passes upwardly through the side wall grates 40. The bottom grate being lower down than usual will add depth to the firebox so that it can hold more material and operate with a heavy fire. As the material accumulates on the bottom grate it overflows the bottom grate and piles up on the side wall grates 40. The valves or doors 105 42^a are then opened so that air is delivered into the conduits 39 to pass upwardly through the grates 40. In this way, the grate surface is increased as the material on the grates accumulates, thus taking care of the 110 increased material and combustion above the grates. The full supply of air is not necessary, however, until the material accumulates over the grates 40. The ashes that drop down through the bottom grate are caught 115 by the truck or car 56, and any ashes that drop down through the grates 40 accumulate in the conduit 39 and may be cleaned out from time to time. When one truck 56 becomes filled it may be moved rearwardly 120 into the tunnel 53, and another truck may be located in the ash pit, so that the filled truck in the ash pit giving off smoke and fumes from the ashes will result in such smoke and fumes being carried with the air into the 125 130

135

1 firebox. The filled truck can thus be left in the tunnel 53 until the ashes thereon stop giving off smoke or fumes, after which the truck may be removed and dumped. The 5 products of combustion from the firebox pass through the opening 66 into the flue 65, and in passing rearwardly through the tubular members 72 the soot, ashes and other particles pass into the flue 67, as hereinbefore 10 described, while the more complete products of combustion remain at the centers of the streams and pass rearwardly through the tubes 73 to the opening 76. The heavier materials pass down through the flue 67 into 15 the tunnel 53 and some if not all of them are returned to the firebox to be consumed. The gases from the basket grate, due to the heating of the wet or green refuse in the basket grate, will pass through the opening 20 60 into the space 61. If the gases leaving the basket grate are clear then the valve 71 may be swung to close the flue 68, so that the gases will pass down in rear of the partition 64 to the opening 76. If the gases 25 leaving the basket grate contain smoke and green gases, the valve 71 is swung rearwardly to close the flue 70 in rear of the partition 64, so that the gases pass down through the return flue 68 into the tunnel 30 53, from which the gases pass through the ash pit 43 and grates so that the smoke and green gases are consumed. Thus, smoke and green gases passing through either of the openings 60 and 66 are returned back to 35 the firebox so that the unburned particles may be burned in returning to the fire.

The gases passing through the opening 40 76 are separated, the valve or damper 78 being opened so that, in addition to the forced draft created by the air discharged through 45 the nozzle 54, there is a natural draft up the smoke stack 75. The flames and more complete products of combustion travel along the center of the stream, as well known, and 50 pass through the center of the flue-way leading from the opening 76 to the opening 77, while the smoke and green gases moving along the sides and top of said flue-way will 55 pass through the slots between the separators 79, 80 and 81 into the space 82. If the natural draft is sufficient then the damper 84 may be opened so that the natural draft 60 will draw the smoke and green gases upwardly through the beds or layers 90 of 65 filtering material which will arrest the particles of soot and other solid matter. If the natural draft is not sufficient for this purpose, then the fan 87 is operated to create a forced draft up through the layers 90 of 70 filtering material, and the filtered gas is discharged from either opening 83 or 85 into the smoke stack. In this way, smoke and green 75 gases are eliminated, so that the gases discharging from the smoke stack will not constitute a nuisance or be obnoxious. It will 80 be noted that the flue-way is tapered or decreases in size from the opening 76 to the opening 77, thereby having a tendency to compress the gases flowing through said flue-way, and the smoke and green gases remaining at the outside of the stream will be crowded through the slots or openings between the separators 79, 80 and 81 into the space 82. The draft extending through the space 82 will serve to draw the smoke and green gases from the separating means, so as not to impair the flow of gases from the furnace to the smoke stack, inasmuch as the gases flowing through the space 82 pass into the smoke stack through the opening 83 or the opening 85 and fan 87. This draft through the space 82 will assist in drawing the smoke and green gases from the separating means through the filtering material 90. The filtering beds or layers 90 may be of any suitable area or extent necessary, and the filtering material may be removed and replaced as often as necessary. The housing 74 has clean-out doors 91 in order that soot and other accumulations may be removed.

Having thus described the invention, what is claimed as new is:—

1. An incinerator furnace comprising a base, walls above the base defining a combustion chamber, a bottom grate within the base, side wall grates between the bottom grate and opposite side walls and forming a firebox with the bottom grate, air conduits extending below and opening through said side wall grates, means for controlling the flow of air through said air conduits, the side walls and base having door openings between them immediately above said side wall grates for access to said firebox, doors for said door openings, and a basket grate between said side walls above the bottom grate for holding material to be consumed and from which the material drops on the bottom grate between the side wall grates. 100

2. An incinerator furnace comprising a base, walls above the base forming a combustion chamber, a bottom grate within the base, side wall grates between the bottom grate and opposite side walls and forming a firebox with the bottom grate, air conduits extending below and opening through said side wall grates, the base having a tunnel extending below the bottom grate, means for blowing air into said tunnel in a direction to pass below the bottom grate, the air conduits having open ends arranged to receive the air blown in a direction to pass under said bottom grate, means controlling the flow of air into said ends of the air conduits, the side walls and base having door openings between them immediately above said side wall grates for access to said firebox, doors for said openings, and a basket grate between said side walls above the bottom grate for 110

115

120

125

130

holding material to be consumed and from which the material drops on the bottom grate between the side wall grates.

3. An incinerator furnace comprising a base, walls above the base defining a combustion chamber, a bottom grate within the base, the base having a tunnel extending below said bottom grate, means for blowing air into said tunnel in a direction to pass under said bottom grate, and a truck movable in said tunnel to a position below the bottom grate to receive ashes passing through said bottom grate and movable to a position beyond the bottom grate and at a point where smoke and fumes rising from the trucks are carried by the air blown into said tunnel to and through said bottom grate.

4. An incinerator furnace comprising a base, walls above the base, grates within said base and forming a firebox, opposite side walls and said base having door openings between them extending the length of said grates and located immediately above said grates to provide access to the firebox throughout the length thereof, a series of doors slideable in each of said openings to be separated at any point throughout the length of the grates, and a basket grate between said side walls above the first named grates for holding material to be consumed and from which the material drops into said firebox at different points of the firebox between the ends thereof.

6. An incinerator furnace comprising a base, a bottom grate in said base, upper side wall beams, hangers depending from said beams, members supported by said hangers above said base, brick walls mounted on said members, a basket grate mounted on said beams and suspended between said walls above the bottom grate, said members and base being spaced apart to provide openings for access to the firebox between said bottom and basket grates, and doors for said openings.

Signed at Washington, D. C., this 29th day of May, 1925.

BERNARD F. SHAUGHNESSY.
